UNITED STATES PATENT OFFICE.

JOSEPH E. BISSELL, OF PITTSBURGH, PENNSYLVANIA.

INTERNAL-COMBUSTION ENGINE.

1,119,228.

Specification of Letters Patent.

Patented Dec. 1, 1914.

Application filed March 2, 1912. Serial No. 681,179.

To all whom it may concern:

Be it known that I, JOSEPH E. BISSELL, residing at Pittsburgh, in the county of Allegheny and State of Pennsylvania, a citizen of the United States, have invented or discovered certain new and useful Improvements in Internal-Combustion Engines, of which improvement the following is a specification.

10 My invention relates to internal combustion engines, and particularly to engines wherein a portion of inert gas of one charge is retained within the expansion cylinder and is compressed with the combustible gas 15 of the successive charge.

The object of my invention is to provide an explosion chamber adapted to prevent the intermingling of the combustible with the inert gas.

20 A further object of my invention is to provide a means for absorbing the heat of combustion in the explosion chamber and radiating such heat to the expanding gases in the cylinder.

25 In the accompanying drawings, which form part of my specification, and in which my invention is illustrated, Figure 1 is a longitudinal sectional view of a gas engine, the plane of section being taken through 30 the axis of the driving shaft, Fig. 2 is a view, partly in section, of the engine shown in Fig. 1, the plane of view being at right angles to the axis of the driving shaft; and Fig. 3 is a view, partly in section, taken on 35 the line III—III, Fig. 1.

In the several figures like numerals are used to designate like parts.

The engine illustrated herein is a two cylinder two-cycle engine having a single compression chamber. It will be understood, however, that my invention is applicable to other forms of engines than that shown herein.

Having reference, first, to the general 45 characteristics of the engine illustrated in the drawings, it will be seen that the cylinders 1 are suitably secured at opposite sides of a casing 2, which forms a compression chamber 3 and bearings for the driving 50 shaft 4. Within each cylinder 1 is a movable piston 5, having crank-arm connection, through the link 6, to the shaft 4. At the

outer end of each cylinder is an explosion chamber 7, 8 (hereafter more fully described); and conduits or passageways 9, 55 (also more fully described hereafter) afford communication between the compression chamber 3 and the explosion chamber 7, 8. Suitable valve-controlled air inlets 10 are secured to the casing 3, which is also provided with suitable openings for the valve-operating rods 11. Each valve rod 11 is provided with a roller 12 and is yieldingly held against a cam 13, rigidly secured to the shaft 4; and each rod is adapted, as shown, 60 to operate an exhaust-port valve 14 and an inlet-port valve 15, the arrangement being such that the exhaust-port is opened before the inlet-port, and closed after the inlet-port. The further elements, in the construction of the engine illustrated herein, consist of igniters 16 placed in the explosion chambers 7, 8, and carbureters 17 placed in the passageways 9.

As will be seen a storage chamber for 75 compressed gas is provided to the end that the combustible gaseous mixture may be held at the maximum pressure obtainable by the downward stroke of the pistons until it becomes desirable to admit such gas into 80 the explosion chamber. Preferably I provide a storage chamber for each cylinder, and I preferably form such chambers as a part of the passageways 9 by closing a portion of the passageways by valves 15 and 85 18. The valves 18 may be held yieldingly against their seats by means of a spring 19, and may be opened by the pressure of the gas beneath the valves. The valves 15 may also be held yieldingly against their seats 90 by means of springs 20, of such strength as to resist the force of the compressed gas in the storage chambers; and the said valves 15 may be opened by the arms 21, connected to the rods 11.

The operation of the engine, as thus far described, is as follows: When the movable parts of the engine are in the positions indicated in the drawings there will be a charge of combustible gas in the explosion chambers 7, 8, and there will be a quantity of air in the compression chamber 3. The combustible mixtures being exploded by the igniters 16, will be effective to drive

the pistons toward the shaft 4, and cause its rotation. At the same time the downward stroke of the pistons will be effective to compress the air in the chamber 3, and 5 drive the compressed air into the storage-chamber portions of the passage-ways 9, the compressed air becoming mixed with a quantity of combustible material as it flows past the carbureters 17. Substantially at 10 the same time as the pistons reach their lowest points the exhaust-port valves 14 are opened, by means of the rod 11 being moved outwardly, and inert gas (gas of combustion) escapes until the expansion chamber 15 spaces in the cylinders are subject to substantially atmospheric pressure. The continued outward movements of the rods 11 become effective, through the arm 21, to open the valve 15 so that a quantity of the 20 explosive mixture will enter the explosion chambers 7, 8 and drive out more of the inert gas. There being now a quantity of inert gas and a quantity of combustible gas in each chamber 7, 8 and the cylinder spaces 25 above the pistons, the valves 14 and 15 are closed and the pistons compress the gases for another explosion. In this operation it will be understood that the upward stroke of the pistons is effective to draw air into 30 the compression chamber 3, the quantity of air entering the said chamber being controlled by the adjustment of the spring in the inlet valve 10.

One feature of my invention resides in 35 the construction of the explosion chamber 7, 8. To the end that there will be substantially no intermingling of the inert gas with the combustible charge, I construct the explosion chamber preferably of two 40 parts, a cylindrical portion 7 and a plurality of tubes 8 leading therefrom. Preferably each tube 8 will be of uniform cross-sectional area throughout, and the sum of the cross-sectional areas of the tubes 8 will 45 preferably be not greater than the cross-sectional area of the cylindrical portion 7. Also the preferred arrangement of the said chamber parts is such as is shown in the drawings, the cylindrical portion being centrally disposed with relation to the cylinder 50 1, and the tubes 8 radially disposed with relation to the cylindrical portion 7.

A further feature of my invention consists in forming the walls of the explosion 55 chamber of heat conducting and radiating material and in so constructing the walls as to absorb the heat generated in the explosion chamber, and radiate such heat to the gases as they expand. To such an end I 60 form the walls, preferably of aluminum alloy and in such a manner as to have a radiating plate 22 at the top of the cylinder. And to the end that a greater portion of the heat of combustion may be available to 65 expand the exploded gases I preferably

cover the cylinders 1 and the explosion chambers 7, 8 with a heat insulator 23 such as a layer of asbestos.

In this particular arrangement it is desirable to adjust the operation of the valves 70 that the combustible mixture, when it is let into the explosion chamber, will flow only to the outer end of the tubes 8, it being understood that, by reason of the fact that the combustible mixture is let into the top of 75 the chamber portion 7, substantially all the inert gas will be driven from the chamber 7, 8, and there will be substantially no intermingling of the combustible with the inert gas. 80

I claim herein as my invention:

1. In an internal combustion engine, the combination with a cylinder, a piston movable within said cylinder, and a compression chamber, of an explosion chamber provided 85 with an igniter and having a plurality of tubes leading from one end thereof, and a passageway affording communication between said compression chamber and the opposite end of said explosion chamber, substantially as described. 90

2. In an internal combustion engine, the combination with a cylinder, a piston movable within said cylinder, and a compression chamber, of an explosion chamber provided 95 with an igniter and having a plurality of radially arranged tubes of substantially uniform cross-sectional area throughout and communicating with said cylinder adjacent to the wall thereof, and a passageway affording communication between said compression chamber and said explosion chamber, substantially as described. 100

3. In an internal combustion engine, the combination with a cylinder, a piston movable within said cylinder, and a compression chamber, of an explosion chamber provided with an igniter and having a plurality of tubes with walls of heat-conducting and radiating material forming adjacent to the 110 gas-expansion portion of the said cylinder a heat-radiating surface, said tubes leading from one end of the explosion chamber, and means for admitting fuel into the other end thereof, substantially as described. 115

4. In an internal combustion engine, the combination with a cylinder, and a piston movable therein, of an explosion chamber centrally disposed at the one end of said cylinder, a plurality of tubes extending laterally therefrom and opening into said cylinder adjacent to the periphery thereof, and a heat radiating plate between said explosion chamber and said cylinder, substantially as described. 120

5. In an internal combustion engine, the combination with a cylinder, a piston movable within said cylinder, and a compression chamber, of an igniter-provided explosion chamber communicating with said 125 cylinder.

cylinder and having a heat transferring plate at the outlet thereof and adjacent to said cylinder, and a passageway affording communication between said compression and explosion chamber, substantially as described.

In testimony whereof I have hereunto set my hand.

JOSEPH E. BISSELL.
